UNITED STATES PATENT OFFICE.

JAMES D. RAY, OF FORT WORTH, TEXAS.

POULTRY FEEDING AND WATERING TROUGH.

Application filed March 26, 1925. Serial No. 18,486.

My invention, which relates to poultry watering and feeding troughs, has reference more specifically to gratings for preventing the poultry from stepping into the trough, 5 while permitting them to insert their heads.

The object of the invention is to provide an extremely simple and inexpensive, yet a very desirable construction, in which transverse strips of metal extend across an elongated opening in a sheet metal plate and are anchored to such plate in a unique manner, 10 to provide the necessary grating or guard.

With the foregoing in view, the invention resides in the novel subject matter herein- 15 after described and claimed, the description being supplemented by the accompanying drawing.

Figure 1 is a front elevation of a device constructed in accordance with my invention.

Figure 2 is a vertical transverse sectional view as indicated by line 2—2 of Fig. 1.

Figure 3 is a longitudinal vertical section on line 3—3 of Fig. 2.

Figure 4 is a sectional perspective view of a portion of the grating.

In the drawing above briefly described, the numeral 1 designates a trough of any desired shape and proportions, but preferably 30 formed of sheet metal, for instance, galvanized iron. I have shown a cover plate 2 hinged at 3 to the back wall of the trough 1 and provided with a downwardly extending flange 4 to surround the upper portion of the trough. The cover may be held in closed 35 position by any desired means.

The numeral 5 designates a longitudinal opening formed in the top plate 2, the metal at the ends of this opening being preferably 40 turned back upon the body portion of the plate to provide reinforcements 6. The metal at the longitudinal edges of the opening is similarly bent back to form a pair of flanges 7 spaced from the body portion of the plate 2. Transverse sheet metal strips 8 extend across the opening 5 and across the flanges 7, the ends of said strips being bent substantially upon themselves to provide hooks 9 which are interposed between and

tightly held by the flanges 7 and the body portion of the plate 2. Preferably, the flanges 7 are distorted adjacent the strips 8 to provide shoulders 10 which abut opposite edges of said strips and thus hold them against longitudinal sliding with respect to 55 the plate 2. In addition to this securing means, the strips 8 may be soldered to the plate 2, as indicated at 11 in Fig. 2, and the co-acting flanges 7 and hooks 9 serve to effectively hold the strips in place while the 60 soldering operation is being performed.

In most instances, I prefer to form the strips 8 of less width at their ends, than throughout the major portions of their lengths, the edges of said major portions being folded upon themselves to provide reinforcing flanges 12.

As excellent results may be obtained from the exact construction disclosed, it may well be followed. However, within the scope of 70 the invention as claimed, modifications may be made and it will be understood that the improved grating formed by the plate 2 with its opening 5, and the transverse strips 8 uniquely connected with said plate, may be 75 used at any desired location in connection with a poultry feeder or waterer.

I claim:

A cover for a poultry feeding and watering device comprising, a sheet metal plate 80 having an elongated opening, the metal at the two opposed longitudinal edges of said opening being turned back to provide a pair of flanges parallel with the body portion of the plate, relatively stationary metal strips 85 extending across said opening and said flanges, said strips having their ends bent substantially upon themselves to provide hooks, the latter being held between said flanges and the adjacent portion of the 90 plate, said flanges being distorted to provide shoulders abutting opposite edges of said strips to hold the latter against movement, longitudinally of the opening.

In testimony whereof I have hereunto af- 95 fixed my signature.

JAMES D. RAY.
